UNITED STATES PATENT OFFICE.

HENRY A. CARPENTER, OF SEWICKLEY, PENNSYLVANIA, AND DANA D. BARNUM, OF WORCESTER, MASSACHUSETTS, ASSIGNEES TO RITER-CONLEY MANUFACTURING COMPANY, OF PITTSBURGH, PENNSYLVANIA, A CORPORATION OF NEW JERSEY.

METHOD OF MANUFACTURING GAS.

1,140,113.

Specification of Letters Patent. Patented May 18, 1915.

Application filed July 24, 1913. Serial No. 720,896.

To all whom it may concern:

Be it known that we, HENRY A. CARPENTER and DANA D. BARNUM, citizens of the United States, residing at Sewickley and Worcester, respectively, in the counties of Allegheny and Worcester, respectively, and States of Pennsylvania and Massachusetts, respectively, have invented certain new and useful Improvements in Methods of Manufacturing Gas, of which the following is a specification.

The prime object of our invention is to provide a new and improved method for the manufacture of gas.

15 The apparatus illustrated in the present invention relates to the type of gas retort constructions shown in United States Letters Patent Number 1,091,111, of March 24, 1914.

20 As illustrated in said patent and as shown herein, we employ several vertical rows of horizontally disposed retorts and a stand pipe interposed between two vertical rows of retorts and in communication with the 25 several retorts of two adjacent rows, whereby gas distilled in the said retorts is introduced to a stand pipe common to the two adjacent rows.

In the accompanying drawing, which illustrates an apparatus for carrying out our method of manufacturing gas, Figure 1 is a front elevational view of a portion of a stack of gas retorts; Fig. 2 is an enlarged sectional view particularly showing a portion of a stand-pipe and valve controlled connections between the superposed retorts and the stand-pipe; Fig. 3 is a detailed view of the valve operating mechanism; and Fig. 4 is a diagrammatic view showing an off-take pipe located at the top of the stack of retorts in place of being at the bottom as shown by Fig. 1, and a gas exhauster and connections between the exhauster and the off-take pipe.

45 Referring to the drawing, 1-1 designate vertically extending stand-pipes, one of the pipes being arranged between two adjacent vertical rows of horizontally disposed retorts 2, and the other stand-pipe arranged 50 in connection with a single row. As illustrated, all of the retorts of each row are connected with a stand-pipe common thereto, or more particularly the mouth-pieces 3 of

the retorts are directly connected with the stand-pipes.

In the form of Fig. 1, the stand-pipes 1 are shown in communication with an off-take pipe 4 located at or near the lower ends of the said stand-pipes, thereby enabling the gas introduced into the common stand-pipe from the several retorts of the adjacent rows of retorts or of a single row to be carried downwardly and into the off-take pipe 4.

In the form of our invention as illustrated by Fig. 4, we show the off-take pipe 5 located at the top of the stack of benches and the pipes 1 in communication with the off-take pipe 5, thus enabling the gas to be carried off at the top of the stack instead of at the bottom thereof as in the form of Fig. 1.

Under our method of manufacturing gas, as will be more particularly hereinafter shown, we dispense with the usual water seal into which the pipes leading from the retorts to the off-take pipe are dipped.

Communication between the stand-pipes and the several retorts is controlled by means of a valve mechanism including, as shown, a valve proper 6 adapted, when in closed position, to rest upon a seat 7 of the mouthpiece, a bent arm 8, a horizontally extending shaft 9 projecting outwardly from the mouth-piece and having its bearing in a casing 10. The outer end of shaft 9 is adapted to engage a tool, not shown, whereby the mechanism is actuated. By means of the valve mechanism, we control the passage of gas from the respective retorts to the stand-pipes, thereby enabling us to shut off at will the discharge of gas from any one or more of the retorts to the common stand-pipe.

In carrying out our method of manufacturing illuminating gas, with two adjacent vertical rows of retorts, or with a single row the retorts are charged and discharged intermittently as to elevation at predetermined intervals. By charging and discharging the individual retorts out of vertical succession, as by a sequence which would separate successively charged retorts by one or more intervening retorts that isolate the retort being charged from that previously charged, thus providing for charging inter-

mittently as to elevation, a reduction in the temperature of the retorts will be minimized, the reduction in temperature due to the charging of the retort not becoming effective upon adjacent retorts to any material degree. During the act of charging, communication between the retorts being charged and the stand-pipe is cut off by the valve controlling the passage of gas between said stand-pipe and retort.

As will be seen, the flow-path of the gas from a retort to a stand pipe is relatively short and formed with a minimum number of abrupt bends in advance of the stand pipe, the structure of the embodiment shown having but the single bend leading from the retort into the lateral, with the remainder of the path substantially straight. As a result, the gas is subjected to a minimum amount of friction in passing from the retort to the stand pipe, and hence practically eliminates the accumulation of pressure (known as back pressure) in the retort during the early stages of the carbonization period when the fresh charge is giving off its largest volume of gas. Back pressure within a retort formed of refractory materials will tend to cause leakage of gas through the retort walls and possibly at the lid of the mouth piece, and the only relief for such condition is to increase the vacuum action of the stand pipe exhauster in order to balance the stand pipe and retort pressures. As a plurality of retorts are connected to the stand pipe, with each retort delivering gas of a carbonization stage differing from the others, large increase in vacuum would tend to produce a somewhat opposite effect on the retorts in which carbonization is well advanced, the tendency being to induce leakage of the products of combustion into the retort, especially where the retorts are formed sectionally. By reason of the practical elimination of such back pressure, the exhauster mechanism preserves the desired uniformities of pressure without wide variations so that the gas in each individual retort will be generated in substantially uniform carbonization stages throughout the carbonization period, especially with respect to temperature, quality and volume, the carbonization period of each retort having a substantially uniform cycle of carbonization stages, the stages representing changes in temperature, quality and volume, as is usual in this art. It will also be seen that the flow path to the stand pipe is so arranged as to render it accessible substantially throughout its length when the retort is opened for charging, so that such deposits in the path as may be produced during a carbonization period can be quickly and readily removed. This permits of cleaning with a minimum expenditure of time and labor, and thus minimizes the period of

exposure of the flow path to the atmosphere, preventing undue chilling. And with the flow path thus readily cleaned, it may be placed in substantially the same condition at the beginning of each carbonization period, with the result that the deposit will be substantially uniform during the period.

It is characteristic of the invention that the gas from each retort will be delivered into the stand pipe with a regular or uniform action throughout the several stages of the carbonization period, the gas stream from each retort preserving its individuality until it enters the stand pipe. As the simultaneous deliveries are of stages differing from each other as to temperature, quality and volume, there is provided such action within the stand pipe as will result in a diffusion therein of the several deliveries, thereby practically destroying the individuality of the several streams and producing an outflow of gas from the stand pipe which is substantially uniform in temperature, quality and volume. This substantial uniformity of stand pipe outflow will vary with variations in the number of retorts connected to the stand pipe, the variations decreasing as the number of retorts so connected increase, this being due to the increased number of chargings in the series of retorts during the length of time corresponding to a carbonization period of a single retort and thereby, decreasing the time interval between successive chargings. In other words, increasing the number of retorts has the effect of increasing the number of different carbonization stages active in the stand pipe at the same time. Obviously, the delivery of the individual streams in approximately definite stage cycles enables the definite relationship between stages being delivered to be substantially maintained.

The advantages of the uniform conditions in the stand pipe produced by the diffusion of the individual deliveries will be readily understood. The uniformity as to temperature results from the fact that the delivery of one stage may be at 500° F. while that of another is at 1200° F., these being the approximate ranges of temperatures, the number of variations between these temperatures depending upon the number of retorts which communicate with the stand pipe. The diffusion of the several deliveries will tend to produce an approximately uniform temperature, the variations being greater or less according to the number of retorts which are delivering. As one of the main causes of stoppages in a stand pipe individual to a single retort is the wide variation in temperature during a carbonization period, it will be readily perceived that by so reducing these variations as to produce an approximately uniform temperature in the stand pipe, this cause for stoppages will be greatly

reduced, and substantial uniformity in quality and volume of the stand pipe output is maintained. Where the series of retorts are charged in an isolation-sequence, the diffusion of the individual deliveries is more rapid owing to the relatively wide differences in conditions existing between the deliveries of adjacent retorts. By reason of the ability to rapidly clean the path leading to the stand pipe and the substantially uniform effect produced within the stand pipe, the effect of stoppages, as a material element in the cost of gas manufacture is reduced to a minimum.

15 In the practice of our method, a gas exhauster 11 in communication with either a bottom of a top take-off pipe is employed, and, as illustrated by the drawing, the gas exhauster 11 is connected with the top off-

20 take pipe 5 by means of a pipe 12. By the employment of the independent valve controlling communication between each of the retorts and the stand-pipes, and the omission of the usual water seal into which the

25 pipes leading from the retorts are entered, we are enabled by means of the exhauster to maintain a direct pull on the stand-pipes and the various retorts and obtain a very desirable regulation of vacuum on the re-

30 torts.

What we claim is:—

1. In the manufacture of coal gas, the method herein described of reducing stand-pipe stoppage, consisting in discharging gas from a plurality of generating retorts directly into a vertical path formed by a stand-pipe and common to all of said retorts, and timing the charging with coal of each retort relatively to the charging of all the other retorts to maintain the temperature of said vertical path substantially uniform.

2. In the manufacture of coal gas, the method herein described of reducing stand-pipe stoppage, consisting in discharging gas simultaneously from a plurality of generating retorts directly and through relatively short lateral paths into a vertical path, said vertical path being formed by a stand-pipe and common to all the retorts, and timing the charging with coal of each retort relatively to the charging of all the other retorts to maintain the temperature of said vertical path substantially uniform.

3. In the manufacture of coal gas, the method herein described of reducing stand-pipe stoppage, consisting in discharging gas from a plurality of generating retorts directly and in lateral direction into a vertical path formed by a stand-pipe and with the gas entering said path at different elevations, and timing the charging of each re-

tort with coal relatively to the charging of every other retort to maintain the temperature of said vertical path substantially uniform.

4. In the manufacture of coal gas, the method herein described of reducing stand-pipe stoppage, consisting in charging a group of retorts with coal at different times and thereby creating overlapping carbonization periods, the time of charging each retort of the group being remote from the time of charging the retorts nearest thereto and thereby minimizing variation in temperature of the retorts and of the gaseous output thereof, maintaining direct communication between each retort during its carbonization period and a vertical path with said path formed by a stand-pipe common to all the retorts, and timing the charging of each retort relatively to the charging of all the other retorts to maintain the temperature of said path substantially uniform.

5. In the manufacture of coal gas, the method herein described which consists in charging in sequence a plurality of gas generating retorts with coal and retaining the charges within the retorts for corresponding periods of time and thereby maintaining overlapping carbonization periods of corresponding duration for all the retorts, discharging the gas from all the retorts directly into a vertical path with said path inclosed by a stand-pipe and common to all the retorts, and timing the charging of each retort relatively to charging of all the other retorts to maintain the composite gaseous stream within said vertical path substantially uniform in quality, temperature and volume.

6. In the manufacture of coal gas, the method herein described, consisting in discharging gas simultaneously from a plurality of generating retorts directly into a vertical path formed by a stand-pipe, said path common to all the retorts and proportioned relatively to the latter to forestall back pressure in any retort, and timing the charging with coal of each retort relatively to the charging of all the other retorts to maintain a gaseous stream within said path of substantially uniform volume.

In testimony whereof we affix our signatures in presence of two witnesses.
